UNITED STATES PATENT OFFICE.

FRANK ALBERT BAKULA, OF ST. LOUIS, MISSOURI, ASSIGNOR TO GROSS CHANDELIER CO., OF ST. LOUIS, MISSOURI, A CORPORATION.

DESIGN FOR A LIGHTING FIXTURE.

Application filed June 29, 1927. Serial No. 22,596. Term of patent 3½ years.

To all whom it may concern:

Be it known that I, FRANK ALBERT BAKULA, a citizen of the United States, residing in the city of St. Louis and State of Missouri, have invented a new, original, and ornamental Design for a Lighting Fixture, of which the following is a specification, reference being had to the accompanying drawings, forming a part hereof.

Figure 1 is a front elevation of a lighting fixture showing my new design.

Figure 2 is a side elevation of a lighting fixture showing my new design.

Figure 3 is a top plan view of a lighting fixture showing my new design.

What I claim is:

The ornamental design for a lighting fixture, as shown.

FRANK ALBERT BAKULA.
